5 Claims. (Cl. 273—200)

ABSTRACT OF THE DISCLOSURE

A golf practice unit, which includes a tethered golf ball. The unit is constructed so that it may readily be inserted into the turf and removed, and yet there is no tendency for the casing of the unit to pull out of the ground when the ball is driven. Also the unit is relatively light, and readily portable.

The present invention relates to an improved golf practicing unit, and it relates more particularly to an improved golf practicing unit which includes a tethered golf ball so as to permit golf swings to be practiced within a limited space.

Many golf practice devices have been developed in the prior art in order to enable the golfer to practice and perfect his golf swing.

One general type of the prior art golf practice device includes a simulated golf ball which is maintained on a pivoted, or flexible, vertical or horizontal arm. Such prior art golf practice devices, however, usually suffer from the disadvantage in that they do not provide the golfer with a sense of having actually "hit" a golf ball, and the golfer soon tires of using such devices.

In addition, the prior art devices of the above-mentioned general type usually require some sort of indicating means to designate whether the "ball" has been hit properly; or whether a "hook" or "slice" has been struck.

A second general type of golf practice device, and the type with which the improved unit of the present invention is concerned, includes a tethered golf ball. This type of device permits the golfer actually to strike a golf ball and to determine whether he has properly hit the ball, all within a limited space.

However, the usual prior art tethered golf ball practice devices of the latter general type, for the most part, have not functioned to return the ball to the golfer, so that time is wasted between practice swings. Moreover, great difficulty has been encountered in the prior art devices in providing adequate securing means for holding such devices in the ground.

This has meant that the prior art devices have been made either so heavy that they cannot be conveniently carried from place to place; or else some means must be provided permanently to install the devices in the ground. This, however, creates inconveniences, since often the golfer desires to carry the practice equipment to a particular locality, such as his back yard, or neighboring park or field; and he also wishes to return the equipment to his home when he has completed his practice.

An object of the present invention is to provide an improved golf practice unit of the tethered golf ball type, which is light and easily portable.

Another object is to provide such an improved golf practice unit which is constructed so that it can be securely anchored on the ground to provide a stable and sturdy support for the tethered golf ball, and yet so that it can be easily removed from the ground, when so desired.

Another object of the invention is to provide such an improved golf practice unit which is strong and sturdy, yet simple and inexpensive in its construction, so that it can be sold at a relatively low price.

2

A still further object of the invention is to provide such an improved golf practice unit which serves to return the ball to the practicing golfer, so that time is not wasted between practice swings, in order to retrieve the ball.

5 Other objects and advantages of the invention will become apparent from a consideration of the following specification, when the specification is taken in conjunction with the accompanying drawing, in which:

10 FIGURE 1 is a perspective representation of a golf swing practice unit constructed in accordance with one embodiment of the invention;

FIGURE 2 is a plan view of the unit of FIGURE 1;

FIGURE 3 is a side elevational view of the unit of

15 FIGURE 1; and

FIGURE 4 is a schematic view of the unit, showing the

unit in place on a practice field.

The golf practicing unit of the present invention includes a casing 10 which, in the illustrated embodiment, has an essentially rectangular configuration. The central portion of the casing 10 is elevated, so that the casing actually has a shape approaching a truncated solid triangle.

20 As shown in FIGURES 1-3, the casing 10 has a forward portion 12, a central portion 14 and a rear portion 16. The central portion 14 has a rectangular aperture 18 formed therein, which extends into the rear and forward portions. The rear portion 16 and forward portion 12 each has a slanting configuration, as best shown in FIGURE 3; so that the casing essentially has the shape of a solid truncated triangle.

25 The casing 10 may be formed of sheet metal, or of an appropriate plastic, or of any other suitable material. A rectangular member 20 is welded, or otherwise affixed, to the underside of the portion 16. The member 20 is formed of relatively heavy material, so as to constitute a weight.

30 The forward portion 12 of the casing 10 has a rim 22 extending transversely across it, and a pair of spikes 24 extend through the rim. The spikes 24 may be affixed to the rim 22 by welding, for example, or by any other appropriate securing means.

35 A pair of coil springs 26 and 28 are attached to the underside of the central portion 14 of the casing 10 by means, for example, of bolts 30 and 32 respectively. These springs extend transversely across the central aperture 18, and their inner ends are coupled together by a ring member 34, so that the springs are held under tension.

40 The golf ball 36 is tethered to the ring 34 by means of a line 38. The line 38 is coupled to the ring 34 by a swivel-type coupler 40. The coupler 40 includes a swivelly mounted portion which receives the line 38, so as to prevent the line 38 from becoming twisted.

45 As shown in FIGURES 3 and 4, for example, the golf ball 36 is teed up a distance behind the unit, as prescribed by the length of the line 38. When the ball is struck, it describes an arc, and draws the line 38 up over the unit.

50 When the ball reaches the end of the line, there is a tendency for the rear end portion 16 to be lifted up from the ground, with a resulting action that the spikes 24 are driven even further into the ground, due to the configuration of the unit.

55 It has been found that the illustrated construction of the unit of the invention provides a stable assembly which has no tendency whatever to be pulled out of the ground during the flight of the struck golf ball.

60 When desired, the unit can be simply removed from the ground, merely by withdrawing it back in the direction of the spikes 24.

65 The action of the coupler 40 prevents the line 38 from becoming twisted, and the springs 26 and 28 serve to return the ball to the vicinity of the practicing golfer, after it has been struck.

The invention provides, therefore, an improved golf swing practice unit which is sturdy and reliable in its operation, and yet which is light and portable. Moreover, the improved golf practice unit of the invention, as explained above, can be manufactured at a relatively low cost and sold at a relatively low price.

It will be observed that the unit of the invention is constructed so that all springs, couplers and mounts are positioned below the top surface of the housing, so that there are no projections above the housing. This obviates any tendency for the line to become tangled when the unit is in use.

Also, the swivel coupler 40 is preferably coupled to the ring 34 at the right hand side in FIGURE 1, as shown. This also has been found to minimize any tendency for the swivel and line to become jammed or tangled in the springs or other components of the unit.

In a constructed embodiment of the invention, the line has a length of 18 feet. This permits the unit to be used conveniently, for example, in a 40 foot space.

While a particular embodiment of the invention has been shown and described, modifications may be made; and it is intended in the claims to cover all such modifications which fall within the scope of the invention.

What is claimed is:

1. A golf swing practice unit constructed to be anchored on the ground and including: a casing having a rectangular shape in plan and having a raised essentially flat horizontal central portion of sheet material with an opening therein, said casing further having essentially flat rear and forward end portions of sheet material sloping down from said central portion in a mutually opposed inclined relation with respect to the plane of said central portion, and said

casing further having a transverse rim at the forward end of said forward end portion; a pair of anchoring spikes affixed to said rim and extending therethrough substantially parallel to the plane of said forward end portion to anchor said casing on the ground; resilient means affixed to the central portion of said casing and extending transversely across said opening; a golf ball; and a line tethering said golf ball to an intermediate point on said resilient means.

10 2. The unit defined in claim 1 and which includes a weight member affixed to the underside of said rear end portion.

3. The unit defined in claim 1 in which said sheet material is sheet metal.

15 4. The unit defined in claim 1 in which said resilient means includes first and second coil springs; and in which said unit further includes an annular member intercoupling the inner ends of said springs, and fastener means for securing one end of said line to said annular member.

20 5. The unit defined in claim 4 in which said fastener means is in the form of a swivel-type coupler.
